SUNSHADE

Murrie C. Bettis, P.O. Box 10816, St. Petersburg, Fla.
Filed Mar. 7, 1963, Ser. No. 263,474
4 Claims. (Cl. 135—7.1)

The present invention relates generally to a sunshade and, more particularly, to a shade which may be readily attached to any type of chair so as to provide an awning-like canopy for the chair. The sunshade according to the present invention is so constructed that it may be attached to any chair having a back support.

There are presently available a wide variety of outdoor type chairs such as, for example, chairs having lightweight metal frames with plastic webbing attached thereto to form body supporting members. While such outdoor chairs may be designed so that they may be easily carried, such chairs do not offer protection against direct sunlight. It has been the practice in the prior art to provide umbrella supports on the chair or on an adjacent table. However, umbrellas are generally heavy and cumbersome and are difficult to position securely. There has been a need for a sunshade which is lightweight, easy to operate and which is readily adjustable to any angle and to fit any sized chair.

According to the present invention there is provided a sunshade for a chair which comprises a frame adapted to be attached to the back of a chair and to which is connected an awning supporting frame in such a manner that the awning is supported above the chair to afford adequate shade for the occupant. The means for attaching the shade to the chair retains the awning firmly in engagement with the chair and yet the attaching means may be readily fitted to various size chairs. Means is provided whereby the angular relation of the awning with respect to the chair may be adjusted.

The present invention includes a supporting frame to which is secured a pair of hanger members which are adapted to engage the upper edge of the back of a chair. Pivots secured to the frame is a pair of hook-shaped members which are adapted to engage the sides of the back of a chair. A spring means urges the hook-shaped members into a retracted position to retain the members in engagement with the sides of the back of a chair. The combination of the hanger members engaging the top edge of a chair and hooks engaging the sides of the back of a chair retain the frame firmly in engagement with the chair and provides an adequate support for the awning which is connected to the frame by means which permits angular adjustment of the awning with respect to the frame supported from the back of the chair.

An object of the present invention is to provide a sunshade for a chair which is adapted to be readily attachable to any sized chair.

Another object of the present invention is to provide an awning or canopy which may be attached to the side and top edges of the back of any chair to provide shade for the occupant of the chair and wherein the singular relationship of the awning or canopy with respect to the chair may be readily adjusted.

Still another object of the present invention is to provide a sunshade which is lightweight and portable and may be readily attached to a chair. The sunshade according to the present invention is economical to construct, requiring a minimum of materials and assembly and thus is commercially feasible.

Other objects and many of the attendant advantages of the present invention will become more readily apparent upon consideration of the following detailed specification in connection with the accompanying drawing wherein:

FIG. 1 is an elevational view taken from the rear of

2

a chair showing one embodiment of the present invention.

FIG. 2 is side elevational view of the embodiment of the sunshade shown in FIG 1,

5 FIG. 3 is broken sectional view along the lines 3—3 of FIG. 2 and showing the ease for connecting the canopy to the supporting frame,

FIG. 4 is a partial elevational view of another embodiment of the invention and,

10 FIG. 5 is broken sectional view similar to FIG. 3 showing a modification of the connecting means between the support frame and canopy.

Referring now, more specifically, to the drawing wherein like numerals indicate like parts throughout the several

15 views there is shown in FIG. 1 as supporting frame 1 comprising a pair of arms 2 and 3 interconnected by a base portion 4. This support frame 1 may be made of any suitable material but most conveniently is a metal bar which has portions 5 and 6 of the base 4 bent so as to 20 extend substantially normally with respect to the remainder of the base. Attached to the portions 5 and 6 of the support frame is a pair of hanger members 7 and 8 which have the upper end portions bent into a generally U-shaped configuration as shown at 9 in FIG. 2. The 25 hanger members 7 and 8 are attached to the base portions 5 and 6, respectively by means permitting swivelling of the hanger members in such a manner that the U-shaped end portions may engage the tops of chairs having various contours.

30 There are provided a pair of L-shaped hook members 10 and 11 which have their inner ends pivoted to the base portion 4 and at 12 and 13, respectively. The outer ends of the hook-members 10 and 11 are provided with forwardly bent generally U-shaped end portions such as 35 shown at 14 in FIG. 2. As is clearly seen in FIG. 1 the intermediate portion of the each of the members 10 and 11 connecting the arms of the L is formed as an eye to provide an attaching point for a spring 15 which urges the arms 10 and 11 to a retracted position so as to retain the hook-shaped end portions of the members 10 and 11 40 in engagement with the sides of the back of a chair as shown. Members 10 and 11 may be disengaged from the sides of the back of a chair by pivoting the members outwardly against the tension of the spring until the end 45 portions of the members 10 and 11 become disengaged from the chair. The pivotally mounted hook members 10 and 11 may be readily engaged with the side edges of chair backs of varying widths.

The spring means interconnecting the members 10 and 50 11 retain the hook-members in engagement with the chair. Thus, the combination of the swivelly mounted hangers 7 and 8 and the pivotally mounted hook-members 10 and 11 permits the support frame 1 to be readily attached to and disengaged from chair backs having a wide variety of contours and of varying widths. The hanger members and side engaging hooks retain the frame in engagement with the chair back firmly and support the frame so that the arms 2 and 3 extend angularly upwardly from the chair back as shown in FIG. 2. Obviously, by varying the configuration of the support 55 frame the angle at which the arms 2 and 3 extend upwardly may be varied.

60 The shade is attached to the upper ends of the arms 2 and 3 of the support frame. The shade comprises an awning or canopy supporting frame 16 and a cover 17. The shade or cover 17 may be made of any fabric, such as denim, canvas, or may be made of plastic or fiberglass. The canopy or awning is crowned so as to cause rainwater to run off. The means connecting the arms 65 of the support frame and the awning permits angular adjustment of the awning with respect to the support frame such as shown in dotted lines in FIG. 2. Such

means may include an elongated rod or shaft 18 having one end portion threaded as at 19 and the other end portion bent as at 20 to form a crank handle. The shaft 18 extends through apertures in the awning support frame 16 and in the outer ends of the arms 2 and 3. A collar 21 is journaled on the shaft 18 between the arms 2 and 3. Secured on the shaft is a locating ring 22. Welded or otherwise suitably secured to the support frame 16 is a nut 23 through which the threaded end portion 19 of the shaft 18 extends. It can be seen that as the shaft 18 is rotated in one direction the support frame will be drawn inwardly against the support arms 2 and 3 which, in turn, are prevented from moving inwardly by the collar 21. Thus, the support frame 16 and canopy will be locked in angular relation with respect to the arms 2 and 3. By rotating the shaft 18 in the opposite direction the threaded end portion will move inwardly on the nut 23 so that the support frame 16 is free to move with respect to the arms 2 and 3 the angular position of the canopy can be adjusted.

In FIG. 5 there is shown another form of means for adjusting the angular relation of the awning and support frame. The arrangement shown in FIG. 5 is particularly useful where a preformed plastic canopy 24 is provided. The arms 2 and 3 of the support frame are retained in engagement with the canopy 24 by threaded studs 25 and 26 which extend through the apron of the canopy 24 and through apertures in the end portions of the arms 2 and 3. Wing nuts 27 and 28 securely retain the canopy in a preselected angular position with respect to the arms 2 and 3. There may be provided a metal race 29 having downwardly turned end portions in order to insure adequate support for the canopy.

In FIG. 4 there is shown another embodiment of the invention wherein the support frame comprises a base portion 30 with arms 31 and 32 integrally formed therewith. The hanger members 33 and 34 are swivelly connected to the base portion in a manner similar to the connection of hangers 7 and 8 and base portion 4 of the FIG. 1 embodiment. Similarly, the L-shaped hook members 35 and 36 are pivotally connected to the base portion 30. These hook members are interconnected by means of spring 37 and function in a manner identical to the members 10 and 11 of the FIG. 1 embodiment. The canopy support frame 38 has a pair of upwardly extending arms 39 and 40 and a canopy is affixed to these arms at the outer ends thereof. The canopy frame 38 is connected to the support frame 30 by means identical to the means shown in FIG. 3. A shaft 41 extends through apertures in the arms 31, 32, 39 and 40. A nut 42 is affixed to the outer face of arm 39 and a threaded end portion 43 on the shaft 41 extends through this nut. A collar 44 is journaled on the shaft between the arms 31 and 32. By tightening the shaft 41 in the nut 42 the arms of the canopy frame become tightly engaged with the arms of the support frame 30 so as to lock the canopy frame in any desired angular position.

It can be seen that according to the present invention there is provided a sunshade which is adapted to be attached to chairs of a wide variety of contours and sizes. The hanger members and side engaging hooks provide firm attachment for the support frame with the back of a chair. Means is provided for angularly adjusting the support frame and sunshade. The attachment is lightweight and portable.

Obviously, many modifications and variations of the present invention are possible in light of the above teachings.

What is claimed as new and desired to be secured by Letters Patent is:

1. A sunshade for a chair comprising a support frame having a pair of arms interconnected with a base portion, hanger members swivelly connected to said base

portion, said hanger members adapted to engage the top of the back of a chair, a pair of hook members pivotally connected to said base portion, spring means interconnecting said hook members, said hook members adapted to be extended to engage the side edges of the back of a chair and adapted to be retained in engaged position by said spring means, an awning frame, a shaft extending through said awning frame and the arms of said support frame, a nut secured to said awning frame, a threaded end portion on said shaft engaging said nut, a collar freely rotatable on said shaft between the arms of said support frame, rotation of said shaft in one direction locking the awning frame against the arms of the support frame, rotation of said shaft in an opposite direction releasing the locking engagement of the support and awning frames so as to permit angular adjustment of the awning frame with respect to the support frame.

2. A shade for attachment to a chair comprising, in combination, a frame, means for connecting a sunshade to said frame, a pair of hanger members mounted on said frame and adapted to engage the top edge of the back of a chair, a pair of hook members pivotally mounted on said frame, spring means operatively associated with said hook members and urging said hook members into a retracted position, said hook members adapted to engage the sides of the back of a chair in an extended position of the hook members whereby said spring means retains said hook members in engagement with the chair and said frame is supported so as to extend generally upwardly from the back of a chair.

3. A sunshade for attachment to a chair comprising a generally U-shaped frame including a pair of arms interconnected with a base portion, an awning support frame, an elongated shaft interconnecting the awning support frame and the outer ends of the arms of the U-shaped frame, means on said shaft whereby upon rotation of the shaft the awning support frame may be locked in a predetermined angular relation with respect to the U-shaped frame, a pair of hanger members secured to the base portion of the U-shaped frame for engaging the top edge of the back of a chair, a pair of hook members pivotally connected to the base of the U-shaped frame, spring means interconnecting the hook members and urging said hook members to a retracted position, said hook members adapted to be extended to engage the side edges of the back of a chair and adapted to be retained in engaged position by said spring means.

4. An attachment which can be mounted upon the back of a chair having an upper edge and side edges to thus position a sunshade secured to said attachment in overlying relationship to the seat of said chair, said attachment comprising a frame adapted to support the sunshade thereon, said frame including an elongated portion which extends across the back of said chair and between the said edges thereon, means mounted on said elongated portion and adapted to engage said chair back upper edge to mount said attachment on said chair, a pair of pivotally mounted members on said elongated portion, said members having hooked ends thereon which are adapted to engage the side edges of said chair back to prevent said attachment from moving relative to said chair, and a spring means extending between said members to bias said members toward one another and to thus retain said hooked ends in engagement with said side edges.
